CLAIM

The ornamental design for a bed, as shown and described.

DESCRIPTION

FIG. 1 is a top, right, first end perspective view of the design; FIG. 2 is a bottom, left, second end perspective view of the design of FIG. 1;

FIG. 3 is a top view of the design of FIG. 1;

FIG. 4 is a bottom view of the design of FIG. 1;

FIG. 5 is a second end view of the design of FIG. 1;

FIG. 6 is a first end view of the design of FIG. 1; and, FIG. 7 is a left side view of the design of FIG. 1, the right side view being a mirror image thereof.

The broken line showing of environment in the drawings is included for the purpose of illustration only and forms no part of the claimed design.
